WRISTWATCH

Jack J. Gillen, P.O. Box 32805, Orlando, Fla.

Filed Feb. 22, 1972, Ser. No. 228,447

Term of patent 14 years

Int. Cl. D10—02

U.S. Cl. D42—8 R

Fig. 1.

Fig. 2.

FIG. 1 is a top plan view of a wristwatch showing my new design, the rear thereof, not shown, is plain and conventional in appearance;

FIG. 2 is a right side elevational view thereof, the left side being a mirror image thereto without the crown.

I claim:

The ornamental design for a wristwatch, substantially as shown.
